COAT STAND OR THE LIKE

Charles H. Dunaway, 16924 Ave. B, Channelview, Tex.

Filed Aug. 23, 1962, Ser. No. 71,430

Term of patent 14 years

(Cl. D33—8)

FIG. 1 is a top perspective view of a coat stand, showing my new design;

FIG. 2 is a bottom perspective view thereof taken from the opposite side;

FIG. 3 is an elevational view thereof as it appears rotated thirty degrees to the left from the position shown in FIG. 1;

FIG. 4 is a sectional view taken on line 4-4 of FIG. 3; and

FIG. 5 is a sectional view taken on line 5-5 of FIG. 3.

I claim:

The ornamental design for a coat stand or the like, substantially as shown.
